FIG. 1 is a perspective view of a combined telephone handset with handle and shoulder rest therefor, showing my new design;

FIG. 2 is a top plan view thereof;

FIG. 3 is a side elevation thereof;

FIG. 4 is a left end elevation thereof;

FIG. 5 is a right end elevation thereof;

FIG. 6 is a bottom plan view thereof;

FIG. 7 is a perspective view of a second embodiment of the design illustrated in FIG. 1;

FIG. 8 is a top plan view thereof;

FIG. 9 is a side elevation thereof;

FIG. 10 is a left end elevation thereof;

FIG. 11 is a perspective view of a third embodiment of the design illustrated in FIG. 1;

FIG. 12 is a side elevation thereof;

FIG. 13 is a bottom plan view thereof;

FIG. 14 is a perspective view of a fourth embodiment of the design illustrated in FIG. 1; and

FIG. 15 is a side elevation thereof.

The undisclosed bottom portions of the handset are conventional.

The characteristic features of my design reside in the specific configuration of the handle and shoulder member as best illustrated in FIGS. 3, 9, 12 and 15.

I claim:

The ornamental design for a combined telephone handset with handle and shoulder rest therefor, substantially as shown and described.
